FREQUENCY CHANGING SYSTEM

Charles Ehrenspurger, Baden, Switzerland, assignor to Aktiengesellschaft Brown Boveri & Cie., Baden, Switzerland, a joint stock company of Switzerland

Application September 20, 1932, Serial No. 634,056,
and in Germany September 25, 1931

14 Claims. (Cl. 172—281)

This invention relates to improvements in alternating current frequency converting systems utilizing electron discharge devices, and more particularly to systems in which a variable amount of in-phase current or of reactive current is to be exchanged in either direction between lines which are not always rigidly maintained in an invariable frequency relation; and is similar in some of its aspects to the frequency converting system disclosed in the joint application of S. Widmer and C. Ehrenspurger, Serial No. 634,055, filed September 20, 1932.

It is well known to connect two alternating current lines or two portions of a single alternating current line by a frequency converter comprising an input transformer, an electron discharge device and an output transformer, in which current supplied from one line to the input transformer is rectified and then converted into alternating current by the electron discharge device, and supplied to the second line through the output transformer. In general, a system of the above character permits connection only of lines rigidly maintained in an invariable frequency relation, and does not permit a regulation of the flow of current in either direction. By energizing the control electrodes of the electron discharge device in dependence on the frequencies of both the input and the output circuits, the system may be made operable for such an energy transfer in either direction between two lines even when the frequency relation between such lines is variable. The controlling means may also be provided with means for adjustment which permit separate regulation of the direction and of the intensity of the flow of in-phase current and of reactive current between the lines.

It is, therefore, one of the objects of the present invention to provide a frequency converting system utilizing an electron discharge device operable for permitting flow of energy in either direction between two alternating current lines which are not rigidly maintained in an invariable frequency relation.

Another object of the present invention is to provide a frequency converting system utilizing an electron discharge device in which the direction of the flow of energy between two alternating current lines which are not rigidly maintained in an invariable frequency relation may be determined by automatically or manually operated control means.

Another object of the present invention is to provide a frequency converting system utilizing

an electron discharge device in which the intensity of flow of in-phase current between two alternating current lines which are not rigidly maintained in an invariable frequency relation, may be determined by automatically or manually operated control means.

Another object of the present invention is to provide a frequency converting system utilizing an electron discharge device in which the intensity of flow of reactive current between two alternating current lines which are not rigidly maintained in an invariable frequency relation, may be determined by automatically or manually operated control means.

Another object of the present invention is to provide a frequency converting system utilizing an electron discharge device in which the voltage induced in the primary windings of the output transformer may be adjusted in phase and in magnitude with respect to the voltage of the output line by automatically or manually operated control means.

Objects and advantages other than those above set forth will be apparent from the following descriptions when read in connection with the accompanying drawings in which:

Fig. 1 diagrammatically illustrates one embodiment of the present invention for converting polyphase alternating currents at one frequency into single phase alternating currents at the same or at another frequency, and in which the flow of in-phase current and of reactive current may be separately regulated both in direction and in magnitude.

Fig. 2 diagrammatically illustrates a modified embodiment of the present invention for converting polyphase alternating current into single phase alternating current and differing from the embodiment shown in Fig. 1 in that the flow of in-phase current and of reactive current may be automatically regulated both in direction and in magnitude; and

Fig. 3 diagrammatically illustrates another modified embodiment of the present invention differing from the embodiment illustrated in Fig. 2 in that the control means are simplified for automatically regulating the flow of only in-phase current both in direction and in magnitude.

Referring more particularly to the drawings by characters of reference, the reference numeral 6 designates a polyphase alternating current line which is shown as a 3-phase line as being the type of line most frequently met in practice. Line 6 may be energized at any com-

mercial frequency, but such frequency need not be maintained at a constant value and may present regular or irregular variations in time. It is assumed that it is desired to transmit energy 5 between line 6 and a single phase alternating current line 7. Line 7 may be energized at any desired frequency and such frequency may be without relation to the frequency of the voltages in Line 6. The frequencies of lines 6 and 7 may be 10 substantially equal as would be the case when such lines are part of electrical systems operated at the same normal frequency. The frequency converting system will be described assuming that it is desired to obtain a flow of energy from line 15 6 towards line 7, and the system elements will be designated accordingly. Line 6 supplies current to winding 8 of an input transformer having two secondary windings 11 and 12 and line 7 is connected with the secondary winding 16 of an 20 output transformer having a primary winding 14. Windings 11, 12 comprise star connected portions such as 11a and 12a etc. severally connected with anodes such as 21a and 22a etc. of an electron discharge device 17 operable as an 25 electric current rectifier and provided with a cathode 18 connected with the neutral point of winding 14. The two portions 14a and 14b of winding 14 are severally connected with the neutral points of windings 11 and 12. Rectifier 17 is provided with control electrodes such 30 as 31a and 32a etc. associated severally with the anodes and usually energized at a negative potential with respect to cathode 18 from a battery 24 through banks of resistances 26 and 27. 35 The control electrodes may also be energized at a positive potential with respect to cathode 18 from a second battery 28 through the segments of a distributor 36 and of two distributors 41 and 42. Distributors 41 and 42 are provided 40 with brushes mounted on the shaft of a synchronous motor 29 energized from line 6 and have their segments spatially adjustable by means of a lever 34. Distributors 41 and 42 are each provided with six segments, the segments 45 of distributor 41 being connected with control electrodes 31a, 31b, etc. and its brush being connected with segment 36a of distributor 36. Distributor 42 is similarly connected with the remaining control electrodes of rectifier 17 and has 50 the brush thereof connected with segment 36b of distributor 36. Distributor 36 is provided with a brush energized from battery 28 rotated by a synchronous motor 37 energized from line 7. The segments of distributor 36 are in contact 55 with the brush thereof during one-half of each revolution of the brush and are spatially adjustable by means of a lever 38.

In operation, assuming that lines 6 and 7 are energized at their respective operating frequencies, winding 16 of the output transformer will be periodically energized at a positive potential 60 from line 7. During each period of positive energization of winding 16, winding 14a must also be energized at a positive potential to permit transfer of energy from line 6 to line 7. During 65 such period, the brush of distributor 36 is in contact with segment 36a thereof thereby energizing the brush of distributor 41 at a positive potential from battery 28. Distributor 42 then 70 has its brush disconnected and is thus inoperative, so that the control electrodes associated therewith are energized at a negative potential from battery 24 and prevent flow of current through winding 12. The brush of distributor 75 41, being rotated by synchronous motor 29, permits sequential energization of control electrodes 31a, 31b, etc. from battery 28 through segment 36a. Such control electrodes are positively energized in the sequence in which the associated anodes 21a, 21b, etc. are energized at 80 positive potentials from winding 11. Winding portions 11a, 11b, etc. therefore sequentially carry current as is well known in the electric current rectifier art, such currents flowing to the cathode 18 of rectifier 17 and combining to form a single current wave flowing through winding 14a back to the neutral point of winding 11. Such current will flow during the entire period during which winding 16 is energized at 85 positive potential, during which time the brush of distributor 36 will remain in contact with segment 36a. During the following half cycle of the voltage of line 7, winding 16 will be energized at a negative potential. Winding 14b then receives current from winding 12, by a process similar to that described above for winding 14a, the flow of such current being controlled by distributor 42. During the period of negative energization of winding 16, the brush of distributor 36 is in contact with segment 36b to 90 permit connection of battery 28 to the brush of distributor 42. The above cycle of successive energization of the portions of winding 14 is repeated during each cycle of the voltage in line 95 7 to permit continuous flow of current from line 6 to line 7. It will be understood that current supplied to winding 8 from line 6 is rectified for a period of time in winding 11 and during another period in winding 12, such cycle of rectification being repeated during each cycle of 100 the voltage in line 7. Windings 11 and 12 thus intermittently transmit direct current to winding portions 14a and 14b, thereby inducing 105 alternating currents in winding 16.

As is well known, when two alternating current generators or converters are supplying current to a common output line, both generators may be considered as supplying current to the current consuming devices connected with the output circuit and also as producing the flow of 110 circulating currents within their own windings and the line. When the voltages of the generators are different in magnitude, a reactive current will circulate through the windings, such magnitude being determined by the difference in 115 the generator voltages and by the reactances of the generator windings. When the voltages of the two generators are out of phase, a circulating current will again be present, such current then being in phase with the line voltage and 120 of a magnitude determined by the phase differences of the generator voltages and by the generator winding reactances. Similarly, in frequency converting systems such as described 125 above, the flow of reactive current between the two lines will be determined by the difference between the induced voltage in the primary windings of the output transformer of the system and the line voltage. The magnitude of 130 such induced voltage may be controlled by adjustment of the segments of distributors 41 and 42 by means of lever 34. As is well known, adjustment of such distributors will cause a change 135 in the rectified output voltage of rectifier 17, which output voltage is applied sequentially to winding portions 14a and 14b and is substantially equal to the induced voltage in such windings. Similarly, adjustment of distributor 36 by means 140 of lever 38 will vary the time of the alternating current cycle of line 7 at which the output volt-

age of rectifier 17 is applied to winding portions 14a and 14b, thereby adjusting the phase angle of the induced voltage in such winding with respect to the voltage in line 7. Such adjustment 5 permits regulation of the flow of in-phase current between the two lines. As is well known in the electric current rectifying art, to permit the flow of reactive current in a system of the character described, it is necessary that each control 10 electrode of the rectifier be energized twice at intervals of about 180 electrical degrees during each cycle of the voltage in line 6. In the present embodiment, such dual energization is obtained by conductively connecting each segment 15 of distributor 41 with a segment of distributor 42 energized one-half cycle later during each cycle of the voltage in line 6.

When it is desired to reverse the transfer of current between the two lines, it being impossible to reverse the direction of current flow 20 through rectifier 17, it becomes necessary to produce the transfer of current when the voltages in lines 6 and 7 are negative instead of positive, such reversal of the voltages determining the reversal of the flow of energy. Such 25 reversal is obtained by shifting the segments of distributors 41 and 42 by 180 degrees, thereby shifting the energization of the control electrodes associated therewith by 180 electrical degrees 30 relative to the voltage in line 6. The segments of distributor 36 are then also displaced by 180 degrees, thereby shifting the energization of the brushes of distributors 41 and 42 by 180 electrical degrees relative to the voltage of line 35 7. The process of current transfer from line 7 to line 6 then becomes similar to the process described above for the transfer of current from line 6 to line 7. Such current transfer occurs 40 through winding portion 14a when such winding portion is energized at a negative potential and also through winding portions such as 11a, 11b, etc. of winding 11, when such portions are also at a negative potential less than the negative potential of winding portion 14a, so that the 45 anodes 21a, 21b, etc. of rectifier 17 are again at a positive potential with respect to cathode 18 to permit flow of current therethrough.

In the embodiment shown in Fig. 2 it is again assumed that current is to be transferred from 50 a three phase line 6 to a single phase alternating current line 7 energized at a frequency which may or may not be the same as the frequency of line 6. In the present embodiment, energization of the control electrodes is obtained 55 through a drum type distributor driven by synchronous motors, the distributor consisting of drums of insulating material with conductive strips of which the development of one drum 52 is shown in the drawings. The distributor drum 60 52 carries, on the surface thereof, two current conducting strips 54 and 55 which are conductively connected with a slip ring 58 whereby they may be energized at a positive potential from battery 28. Current is transmitted from 65 strips 54 and 55 to a plurality of brushes 59, each brush being a strip of current conductive material wound as a helix on a second distributor drum of insulating material 61. Each brush or helix 59 is conductively connected with 70 one of a plurality of slip rings 62 whereby the voltage of battery 28 may be applied to control electrodes such as 31a through resistances 27. Helices 59 are equal in number to 75 the number of portions of winding 11 and may make one or several revolutions on drum 61.

Drum 52 is also in contact with a second set of electrical brushes 63 mounted on a distributor drum 64 and connected with slip rings 68 for energizing control electrodes such as 32a associated with the several portions of winding 80 12. Drums 61 and 64 are mechanically connected for synchronous rotation thereof and are driven by a synchronous motor 69. Motor 69 may have the armature thereof energized from line 6 and the field thereof energized from line 7, thereby 85 permitting rotation of drums 61 and 64 at a speed depending upon the relative frequencies of lines 6 and 7. When lines 6 and 7 are energized at exactly their normal frequencies, the armature of motor 69 will remain stationary. 90 Drum 52 may be connected with its motor 37 through a mechanical coupling to permit adjustment of the relative angular position of the distributor and the motor during simultaneous rotation thereof; such coupling is adjustable by movement of a lever 70 which may be controlled manually or which may be actuated by a solenoid 72 energized in response to the current in line 7 through a current transformer 73. Similarly, drums 61 and 64 may be connected with motor 69 through another coupling 74 to permit the adjustment of the angular relation thereof, such coupling being adjusted by movement of a lever 75 which may be actuated by a solenoid 76 energized in response to the 105 voltage of line 7.

In operation, the control electrodes of rectifier 17 are generally maintained at a negative potential relative to the potential of cathode 18 by means of battery 24. Assuming that it is 110 desired to transfer energy from line 6 to line 7, and assuming that the voltage in line 7 at the instant considered is such that winding 11 is to be brought to a positive potential, rotation of synchronous motor 37 brings strip 54 115 of distributor 52 into sequential contact with the different electrical brushes 59 assembled on drum 61. The control electrodes associated with the portions of winding 11 are thus sequentially brought to a positive potential and 120 permit sequential operation of the associated anodes. Winding 11 therefore carries alternating currents at the frequency of the voltage of line 6, such currents combining at cathode 18 to form a single current impulse through winding portion 14a back to the neutral point of 125 winding 11. After one-half cycle of the voltage of line 7, strip 54 of distributor 52 will have rotated by one-half of a revolution and will come into sequential contact with brushes 63 130 mounted on drum 64. By a process similar to that described above, winding 12 thereupon produces a wave of rectified current circulating through winding portion 14b. Such changing 135 energization of winding portions 14a and 14b are repeated at the frequency of the voltage in line 7, thereby inducing, in winding 16, an alternating current at the frequency of line 7. During each half cycle of the voltage in line 7, the time of sequential energization of the 140 control electrodes of rectifier 17 is determined by the time of contact of strip 54 with electrical brushes such as 59. The shape of strip 54 will therefore determine the sequence of energization of the portions of winding 11 during 145 half cycle periods of the voltage in line 7. By giving to strip 54 a suitable shape, it is possible to so determine the sequential energization of the portions of windings 11 and 12, that the waves of current transmitted to winding 14 150

approximate the sinusoidal shape. In the present embodiment also, it is necessary that the control electrodes of the rectifier be energized at a positive potential twice during each cycle 5 of the single phase line voltage. To obtain such result, drum 52 is provided with a second conductive strip 55 which contacts with each of helical brushes 59 and 63 about 180 electrical degrees after strip 54 makes such contact. As 10 in the embodiment illustrated in Fig. 1, the intensity of flow of reactive current is determined by the time of energization of the control electrodes of the rectifier relative to the voltage cycle of the 3-phase line. Such time of 15 energization may be adjusted by adjustment of coupling 74, such adjustment being attained manually or, if desired, automatically in response to the variations of any electrical quantity such as the voltage in line 7 by means of 20 solenoid 76. When the relation between the frequencies of the voltages of lines 6 and 7 is at its rated value, motor 69 is at a standstill and a constant value of the reactive current exchanged between lines 6 and 7 is obtained 25 automatically. When the frequencies of the voltages in lines 6 and 7 vary from their rated relation, motor 69 rotates drums 61 and 64 to reestablish the proper sequence of energization 30 of the control electrodes of the rectifier to permit continuation of the flow of current at its original value.

As in the embodiment illustrated in Fig. 1, the flow of in-phase current is determined by the time of energization of the control electrodes 35 controlling each winding 11 and 12 relative to the voltage wave of the output line 7. Such energization may be adjusted by varying the position of coupling 71 by means of lever 70, such adjustment being also obtained, if so desired, 40 by means of solenoid 72 energized from current transformer 73. It is also possible to reverse the direction of the flow of energy between the two lines, the flow of reactive energy being reversed by adjustment of coupling 74 to 45 permit displacement of the energization of the control electrodes by an angle of 180 electrical degrees with respect to the voltage of line 6 and the flow of in-phase energy being adjusted by means of coupling 71, thereby displacing the 50 energization of the control electrodes by 180 electrical degrees with respect to the voltage wave of line 7.

In the embodiment illustrated in Fig. 3, the control of rectifier 17 is shown as simplified to 55 permit flow of only in-phase current between lines 6 and 7. In the present embodiment, the control electrodes are connected into two groups, severally associated with windings 11 and 12, the two groups being connected with the terminals 60 of a single phase generator 77 driven by synchronous motor 37 energized from line 7. Generator 77 is connected with motor 37 through coupling 71 as in the embodiment shown in Fig. 2. Coupling 71 may be adjusted by hand 65 or may be adjusted according to any predetermined schedule applied through means herein represented as a timing mechanism 81.

In operation, assuming that winding 11 is to 70 receive a positive current impulse to be transmitted to line 7, coupling 79 is so adjusted that the control electrodes 31a, 31b, etc. associated with winding 11 are all energized at a positive potential with respect to the cathode from generator 77. The anodes 21a, 21b, etc. severally 75 connected with the portions of winding 11 are,

therefore, all operable for carrying current, and winding 11 will produce rectified currents which combine at cathode 18 into a single current impulse transmitted over winding portion 14a back to the neutral point of winding 11. During the next half cycle of the voltage of line 7, generator 80 77 maintains the control electrodes associated with winding 11 at a negative potential, thereby making winding 11 inoperative. The control electrodes 32a, 32b, etc. associated with winding 12 are then energized at a positive potential 85 so that, by a process similar to that described above, a current impulse is sent through winding portion 14b. Current impulses are thus sent through winding portions 14a and 14b during 90 each cycle of the voltage in line 7, thereby inducing in winding 16 an alternating current transmitted to line 7. As in the embodiments previously described, the intensity and the direction of flow of in-phase current circulating between the two lines is determined by the time of 95 energization of the control electrodes relative to the voltage wave of line 7. In the present embodiment, such time may be varied by adjustment of coupling 71, thereby shifting the output voltage of generator 77 with respect to the voltage of line 7. This adjustment may be obtained by hand or in response to the variation of electrical or mechanical quantities and may be obtained, as shown in Fig. 3, by means of a timing 100 mechanism 81.

Although but a few embodiments of the present invention have been illustrated and described, it will be apparent to those skilled in the art that various changes and modifications may 110 be made therein without departing from the spirit of the invention or from the scope of the appended claims.

It is claimed and desired to secure by Letters Patent:

1. In a system for transmitting energy between alternating current lines, an alternating current line of one frequency, a transformer connected with said line, an electron discharge device having anodes with associated control electrodes 120 and a cathode, the anodes and the cathode of said device being connected with said transformer, an alternating current line of a frequency other than that of the first said line, a transformer connecting the cathode of said device 125 with the second said line, said transformers being interconnected, a source of potential arranged for connection with the control electrodes of said device, and means cooperatively controlled in response to the frequencies of said 130 lines for controlling the connection of said source with the control electrodes to vary the energy flow between said lines.

2. In a system for transmitting energy between alternating current lines, an alternating 135 current line of one frequency, a transformer connected with said line, an electron discharge device having anodes with associated control electrodes and a cathode, the anodes and the cathode of said device being connected with said 140 transformer, an alternating current line at a frequency other than that of the first said line, a transformer connecting the cathode of said device with the second said line, said transformers being interconnected, a source of potential 145 having anodes with associated control electrodes of said device, and means for controlling the connection of said source with the control electrodes to control the direction of the energy flow between said lines.

- said transformer, an alternating current line at a frequency other than that of the first said line, a transformer connecting the cathode of said device with the second said line, said transformers being interconnected, a source of potential arranged for connection with the control electrodes of said device, a distributor having a plurality of movable drums for controlling the sequential connection of the control electrodes 5 80
- 10 with said source, a motor for driving one of the drums responsive to the frequency of one of said lines, and a motor for driving the other drums of said distributor in response to the frequency differences between said lines.
- 15 11. In a system for transmitting energy between alternating current lines, an alternating current line at one frequency, a transformer connected with said line, an electron discharge device having anodes with associated control electrodes and a cathode, the anodes and the cathode of said device being connected with said transformer, an alternating current line at a frequency other than that of the first said line, a transformer connecting the cathode of 20 85
- 25 said device with the second said line, said transformers being interconnected, a source of potential arranged for connection with the control electrodes of said device, a distributor having a plurality of movable drums for controlling the connection of the control electrodes with said source, a motor for driving one of the drums responsive to the frequency of one of said lines, a motor for driving the other drums of said distributor in response to the frequency differences 30 90
- 35 between said lines, and means for automatically varying the relative angular positions of said distributor and said motors, said means being responsive to predetermined conditions affecting 100
- 40 operation of the system. 95
12. In a system for transmitting energy between alternating current lines, an alternating current line at one frequency, a transformer connected with said line, an electron discharge device having anodes with associated control electrodes and a cathode, the anodes and the cathode of said device being connected with 45 105
- 50 said transformer, an alternating current line at a frequency other than that of the first said line, a transformer connecting the cathode of said device with the second said line, said transformers being interconnected, a source of potential arranged for connection with the control electrodes of said device, a distributor having a plurality of movable drums for controlling the connection of the control electrodes with said source, a motor for driving one of the drums responsive to the frequency of one of said lines, a motor for driving the other drums of said distributor in response to the frequency differences 55 110
- 60 of said distributor responsive to the frequency of one of said lines, a motor for driving the other drums of said distributor in response to the 115
- 65 120
- 70 125
- 75 130
- 80 135
- 85 140
- 90 145
- 95 150
- 100
- 105
- 110
- 115
- 120
- 125
- 130
- 135
- 140
- 145
- 150

CHARLES EHRENSPERGER.

CERTIFICATE OF CORRECTION.

Patent No. 1,934,227.

November 7, 1933.

CHARLES EHRENSPERGER.

It is hereby certified that error appears in the printed specification of the above numbered patent requiring correction as follows: Page 4, line 146, claim 2, strike out the words "device having anodes with associated" and insert instead the syllable and words tential arranged for connection with the; page 5, line 134, claim 9, for "niterconnected" read interconnected; and that the said Letters Patent should be read with these corrections therein that the same may conform to the record of the case in the Patent Office.

Signed and sealed this 12th day of December, A. D. 1933.

F. M. Hopkins

Acting Commissioner of Patents.
